UNITED STATES PATENT OFFICE

MICHEL ABOOD, OF JACKSONVILLE, FLORIDA

REFRIGERATED DISPLAY CASE

Application filed January 27, 1930. Serial No. 423,828.

This invention relates to refrigerated display cases and particularly to the method of refrigerating by ice and brine method.

An object of the invention is to provide a device of the character referred to that utilizes not only the ice and brine containers, for refrigerating a show case or other storage compartment, but makes use of the refrigeration produced from the drainage pipes that carry the brine solution away from the container.

Further objects of the invention are to provide, in a manner as hereinafter set forth, a device of the character referred to, that is strong, compact, and durable, thoroughly reliable for its intended purpose, producing perfect refrigeration without dehydrating the storage compartment, that is very attractive in appearance, that is very simple in its operation, and economic in assembly and that is comparatively inexpensive to manufacture.

With the foregoing and other objects in view, the invention consists of a novel construction, combination and arrangement of parts as will be hereinafter more fully and specifically described and illustrated in the accompanying drawings, wherein is disclosed an embodiment of the invention, but it is to be understood that changes, variations, and modifications may be resorted to without departing from the spirit of the claims hereto appended.

In the drawings wherein like reference characters designate like parts corresponding throughout the several views:

Figure 1 is a front elevation of a show case in which the present invention is installed,

Fig. 2 is a rear elevation thereof,

Fig. 3 is a detailed, vertical longitudinal section therethrough,

Fig. 4 is a transverse vertical section in detail, taken substantially on line 4-4 of Fig. 1,

Fig. 5 is a vertical, transverse, detailed section, taken substantially on the line 5-5 of Fig. 2 and looking in the direction of the arrows.

Referring to the drawings in detail, 6 rep-

resents a conventional built-in counter, upon which the show case of the present invention rests so as to be a height from the floor to permit easy vision by the prospective buyer. The display case, in accordance with the present invention is constructed on a base indicated generally at 7, and rests upon the counter 6.

At each end of the base 7 there are formed chambers 8, 9 and extending between these two chambers is a refrigerated storage compartment indicated generally at 10. The base 7 forms a continuous bottom for chambers 8 and 9 at the storage compartment 10, and is substantially flat on its upper and lower face.

This base 7 is rectangular in configuration and formed with vertically spaced sheet boards 11, 12 spaced apart by spacer blocks at intervals throughout its length. Of course the ends and side walls are closed by sheathing 14. Between the sheathing boards 11, 12 is a layer 15 of cork insulating and superimposed on the upper sheathing boards 12, is a layer of paper 16 upon, which rests a ply of felt 17.

Rising perpendicularly from the base 7 at its opposite ends, are the four walls of the chambers 8, 9. In horizontal section, the chambers are substantially rectangular and are formed with an open top. As aforementioned, the base 7 forms the bottom wall of the chambers 8, 9. The chambers 8, 9 are each formed in the same manner, and it is believed that a description of the one, will teach a clear understanding of the other.

Interiorly of the upstanding walls of the chamber there is a substantially rectangular space 18, the purpose of which will presently appear. Each of the four walls of both chambers are formed on the outside with sheathing boards 19 spacing from the inner sheathing board 20 and in the spaces between the sheathing boards is attached a relatively thick course of insulating corks 21. Next to the inner sheathing board is secured a layer of heavy fiber 22 which is held in place by a metal sheathing 23.

The outer sheathing boards 19 project above the upper edges of the inner sheathing boards 20 so as to extend to and be se-

cured in a right angled notch in the perimeter of the cover plate 25, that closes the upper ends of the upstanding walls. Hingedly mounted on the cover plate 25 as at 26, are 5 lids 27 properly insulated that close the upper ends of the space 18 between the walls of each chamber.

A portion of the rear wall R of the storage compartment 10 is solid and vertically disposed. 10 This solid portion of the rear wall includes upstanding, transversely spaced inner and outer sheathing boards 30, 31, the bottom edges of which are secured to the base 7. The sheathing boards are co-extensive 15 with the length of the compartments 10 and have a layer of cords 32 between and to form a proper insulation.

Supported on upper edges of the sheathing board as at 33, and sealing the top thereof, 20 rests the lower edges of a wooden frame indicated generally at 34. A cross sectional area of the frame 34 will clearly appear from Fig. 5 of the drawings. A space within this frame 34 provides a storage compartment 36. The 25 ends of the frame 34 are secured in abutting relation to the inner walls of the respective chambers, 8, 9 whereby the inner walls are continuous with the ends of compartments 36.

It will therefore be apparent that some 30 refrigeration will be produced by these inner walls that form the ends of the compartment. The front of the frame 34 is indicated generally at F and includes an integral upwardly inclining rectangular frame 37, in which is supported three, spaced plies of glass 38 that not only provide a proper insulation from the front of the compartment 10, but also permit vision of the customer into the compartment. Integral with the front frame 37 35 is the top frame 39 that is horizontally disposed and supported thereon are three spaced panels of glass 40. The frame 39 and the glass 40 form the top wall of compartment 36.

The rear wall of frame 34 is provided with 40 a plurality of openings 41, that are closed by the door frames 42 that are hingedly connected as at 43 to the rear edge of the top frame 39.

Disposed across the door frames 42, are 45 three, spaced plies or glass panels 44, which permit vision into the compartment 36 and also provide proper insulation. Any number of doors may be provided, depending upon the length of the storage compartment 36 and the size of articles to be stored therein. The frame 34 with the glass panels and the short wall formed by sheathing boards 30 and 31, provide the sides of the refrigerating compartment 36.

Supported in each of the chambers 8, 9 are 50 metal containers 44 and 45, that are substantially the same configuration as the space 18 and the bottom wall 46 is spaced above the upper face of the base 7 to provide a space for

an elongated drip pan, 47 to extend throughout the length of both chambers and the storage compartment 36.

The drip pan 47 tapers slightly from each end toward the center and depending therefrom is a drain pipe 48 extending through the base 7, and into the proper drain. As best seen in Figure 4, the pan 47 terminates in enlarged end portions which are disposed beneath the containers 44 and 45. This drip pan 47 carries away condensation from the containers 44, 45, and the brine pipes to be presently described.

Extending throughout the entire length of the storage compartment 36, are a plurality of pipes 49 preferably vertically spaced and having a very slight inclination toward the center of compartment 36 from each end. One end of the plurality of pipes 49 is connected by a suitable fitting 50, to container 44, while the opposite ends of each plurality of pipes are connected by suitable fittings 51 to the container 45.

These plurality of spaced pipes 49 are preferably disposed toward the rear of the container and the lowermost one of the pipes projects through each container substantially flush with the bottom walls 46. The other pipes of the plurality are stepped above the lowermost one in a vertical plane, so as to carry the brine at various levels from the containers.

In the center, the plurality of containers are connected with, in any suitable manner, a single tubular trap 52, that has a conductor 53 leading from its bottom wall into the drip pan 47. In the event the trap 52 would become clogged, or frozen, there leads from the closed top 54 thereof, an overflow pipe 55 that also leads into the drip pan 47.

The plurality of vertically spaced pipes 49 is extended through the inner walls of each chamber 8, 9. In the operation of the invention, broken ice and salt are placed in each container 44, 45. The ice melts and forms a solution with the salt and enters the plurality of spaced conductor pipes 49 as brine, and this circulation of brine through the pipes will provide a very even low temperature in the storage compartments 36 whereupon food displayed therein for sale will not only be attractive to the customer, but will be kept in a state of preservation.

The present embodiment of the invention has been disclosed in considerable detail merely for the purpose of exemplification since in actual practice, it attains the features of advantage enumerated as desirable in the statement of the invention and the above description.

It is to be understood that by describing in detail herein any particular form, structure, or arrangement, it is not intended to limit the invention beyond the terms of the several claims, or the requirements of the prior art.

Having thus described my invention, what I claim as new is:—

1. A refrigerated display case of the character described having end compartments and further having an intermediate display compartment extending between the end compartments and having communication with the lower portions thereof, containers mounted in the end compartments for the reception of a cooling medium, said containers having their bottoms spaced above the bottoms of the end compartments, a series of pipes traversing the display compartment and having their ends connected to the containers for the reception of the cooling medium therefrom, a drip pan disposed in the display compartment beneath the pipes to receive condensate therefrom, said drip pan extending into the end compartments and terminating in enlarged end portions disposed beneath the containers for receiving condensate therefrom. 70
2. A refrigerated display case of the character described having end compartments and further having an intermediate display compartment extending between the end compartments and having communication with the lower portions thereof, containers mounted in the end compartments for the reception of a cooling medium, said containers having their bottoms spaced above the bottoms of the end compartments, a series of pipes traversing the display compartment and having their ends connected to the containers for the reception of the cooling medium therefrom, a drip pan disposed in the display compartment beneath the pipes to receive condensate therefrom, said drip pan extending into the end compartments and terminating in enlarged end portions disposed beneath the containers for receiving condensate therefrom, and a trap, common to all of the pipes, interposed in said pipes to receive the cooling medium therefrom, said trap being disposed in the display compartment above the pan and having an outlet in its lower end for discharging the cooling medium into the pan. 80
3. A refrigerator display case of the character described having vertical end compartments and further having an elongated, intermediate display compartment extending between the end compartments and having its ends in communication with the lower portions of the end compartments, containers in the end compartments for the reception of a cooling medium, the bottoms of the containers being spaced above the bottom of the compartments, a series of vertically spaced, parallel pipes traversing the display compartment adjacent one side thereof, said pipes having their ends connected to the containers at vertically spaced points to receive the cooling medium therefrom, an elongated drip pan disposed in the display compartment beneath the pipes, said pan extending 85
